UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 12,877, dated April 11, 1882.

Application filed February 23, 1882. Term of patent 34 years.

To all whom it may concern:

Be it known that I, JULIUS PEGEL, of New York city, in the county and State of New York, have invented a new and original Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

The blank field *a a a* underlies the greater part of the design, being broken only by the blank fields *b c*—the former somewhat arched and the latter somewhat triangular in shape—and the irregular field *i*. Over the fields *b* and *c*, at their upper edges, project for a short distance portions of the field or ground *a* in the form of lichen or coral-like sprays jutting from *a*, and the lower portions of both *b* and *c* are traversed by bouquets of flowers and leaves springing from those parts of *a* immediately below said *b* and *c*. The field *i* (shown partly on each side of the photograph) is mostly ornamented by small rectangular fret-work, has an outline on the right resembling ascending steps, and is traversed in parts by flower groups.

30 *A* is the bouquet, portions of which traverse the lower part of *b* and project up into the ground *b*, being set out prominently thereby. *A* consists above of two small star-shaped flower clusters, *o* and *d*, springing from a bunch of flag-leaves, *e*; centrally the large cluster *B*, massed roses and small flowers, and geranium and other leaves; on the left the small star-shaped flower bunch *f*, and on the right two similar bunches, *g* and *h*, the various parts of *A* overlying and partially concealing adjacent figures.

35 *C* is a border, bounding *b* on the right, consisting of a series of heart-shaped figures, encircling line-work, and intervening darts. *D* is a large bouquet traversing *a* directly over *b*, and consisting of two large five-petaled flowers centrally, with small star-shaped

flowers and blossoms above and to the left, all supported on and surrounded by a mass of leaves.

50 *E*, to the left of *D*, is a cluster of small star-shaped flowers.

55 *F*, to the right of *D*, and shown in part on each side of the photograph, part of it having the form of an inverted **V**, is a border with a series of pendent darts above and a Grecian ornament below, and in part forms the upper boundary of the field *c*, being traversed by the lichen or coral-like forms that project into the field *c* below.

60 From *E* to *F* springs the arch *G*, consisting of a series of separate sprays of lichen or coral-like forms bearing small blossoms. This arch *G* leaves portions of the field *a* blank between it and the group *D*. Above *G*, and 65 arching with it, is the figure *k*, ornamented by small rectangular fret-work traversed by the sprays of *G*, and its upper outline presenting the appearance of two series of ascending steps approaching above, and, with 70 their common step, the keystone of the arch, supporting the wide border *H*, from which the flower group *A* springs. *H* consists of a band below, ornamented by small cross-shaped figures, a narrow middle band with triangular 75 ornaments, and a broad band above, mostly concealed by *A*, ornamented by squares placed diagonally, with square centers.

75 Under the left foot of the arch *G* *k* is the horizontal border *l*, consisting of a series of 80 small heart-shaped leaf forms with small crosses between, and below *l* the horizontal and vertical border *m*, consisting of a series of squares with star-like centers below and a series of small triangles above. *m* forms the 85 upper and right-hand boundary of the irregular figure *n*, (shown in part on each side of the photograph,) forming part of the blank field *a*. *n* is traversed on the right by parts of the group *f*, and centrally by the leaf group *K*, 90 having projecting flower-clusters above.

85 *L* is a bouquet, which traverses the lower portions of the field *c*, and projects down into the field *i* and over adjacent figures, and con-

sists of two large roses supported on a mass of leaves and flanked and surmounted by star-shaped flowers and buds.

I claim—

- 5 1. The design for carpets, consisting of the group A, including the groups *o d e B f g h*, substantially as shown.
2. The design for carpets, consisting of the group D, substantially as shown.
- 10 3. The design for carpets, consisting of the figures *D E G k*, substantially as shown.

4. The design for carpets, consisting of the group *L*, substantially as shown.

5. The design for carpets, consisting of the groups and figures A, including *o d e B f g h*, and *k l m n*, and the ground *a b c i*, substantially as shown.

JULIUS PEGEL.
